CHUCK FOR GRIPPING BARS

André Cauchois, Lille, France

Application March 3, 1948, Serial No. 12,737
In France March 21, 1947

4 Claims. (Cl. 279—73)

1

The present invention relates to a chuck for gripping bars, which is to be placed on a machine having a movement of rotation.

It is characterized by a double-coned ring formed with a neck on each side and with radial channels, in which there slide, parallel to their longitudinal axes, rollers of which one head part with spherical surface receives the thrust of two coned recesses of the same aperture, one fixed and the other guided by a number of keys, which approach one another under the action of a screw-threaded annulus or rod screwing into the central bore of the moving conically recessed ring, the rotation of this screw-threaded annulus or rod being produced by a set of coned gears which can be manipulated or operated by means of an external key, a ball-thrust being arranged between this threaded rod and the inner end of the chuck body.

It is further characterized by the arrangement along two diametrically opposite generatrices of each roller or half-channels closed at one end, in which are partially located cylindrical springs, the other part of which is located in corresponding half-channels closed at one end and formed in the ring accommodating the rollers.

Another characteristic consists in the feature that the double-coned ring maintaining the rollers comprises tenons which slide in guide slots formed in the body of the chuck and prevent this ring from turning.

As an alternative form, it is further characterized by the replacement of the spherical end of the rollers with a frusto-conical end.

The end of each of the rollers forming the jaw has two chamfered surfaces.

The accompanying drawings show diagrammatically by way of example one form of construction of the invention.

Figure 1 is a longitudinal axial cross section of the chuck.

Figure 2 is a front view, with a part in cross section, of the ring with its tightening or gripping rollers.

Figures 3, 4 and 5 are views of a gripping roller on a larger scale from above, from the side and from below respectively.

Figure 6 shows on the larger scale a side view of a tightening roller terminating in a frusto-conical part.

In Figure 1 can be seen at 1 the body of the chuck, the bottom or inner end of which is closed by a cast-on member 2, possessing a recess 3, coned or cylindrical, for fixing to the machine.

This chuck body is closed by a cap 4, held in

position by a screw-threaded ring 5. The cap 4 has on the inside a coned recess 6 of the same aperture as the conical recess 7 of an annulus 8 sliding in the body of the chuck, the bore of which is internally screw-threaded. Thus annulus 8 is guided longitudinally by one or more keys 9, which are solidly connected therewith and slide in slots 10 formed in the internal bore of the chuck.

Between the coned recesses 6 of the cap and 7 of the annulus 8 are pressed the heads of rollers 11. These rollers are located in channels formed radially in a double coned ring 13 comprising cylindrical neck parts 12 and 12' and having pins 14 which can slide in the slots 10, serving to guide the keys 9 of the annulus 8.

Into the internal screw-threaded bore of the annulus 8 is screwed a member 15, provided with a flange 16, the edges of which are cut as a bevel gear 17, so as to form a bevel pair with a gear 18, which is rigid with a key 19, the end 20 of which can pivot in a cavity formed in the bottom 2 of the chuck.

The flange 16 of the part 15 is maintained at the side of the head of the chuck by means of a resilient ring or guard ring 21.

Between the inner end of the part 15 and the inner end of the bottom 2 of the chuck is arranged a ball thrust bearing 22.

Each roller 11 has two diametrically opposite lateral slots 23 and 24, closed at one end, corresponding to two similar slots 25 and 26 formed in the ring 13. These two slots register with one another and form locations for cylindrical springs 27, one end of each of which bears on the roller 35 and the other end on the ring. The purpose of these springs is to separate the rollers when the chuck is slackened, and they form at the same time guides and keys to prevent the rollers from turning in their location.

As shown in the drawings, the base of the roller forming a jaw possesses two chamfers 28 and 29, having between them a plane part 30 forming the gripping surface, which may with advantage be knurled as shown in Figure 5.

As shown in Figure 6, the head of the roller may have a conical surface instead of a spherical surface.

The chuck formed according to the invention has the following advantages:

Great gripping power without overhang of the jaws; rigorous precision in consequence of the ease of machining of the parts; large gripping surface of the jaws; reduced overall dimensions for a large gripping power.

I claim:

1. A roller chuck for gripping bars, comprising: a chuck body formed with a frusto-conical recess at its inner end, an annulus longitudinally slidable and guided in the chuck body, the annulus being formed with a frusto-conical recess facing and co-axial with that of the chuck body, a ring located between and co-axial with the said frusto-conical recesses, the ring being formed with radial guiding apertures and also with two externally frusto-conical surfaces facing the frusto-conical recesses, neck portions projecting axially from the said ring, one of the said neck portions being guided in the sliding annulus, and the chuck body being formed with a longitudinal aperture for guiding the other neck portion, rollers radially slidable in the apertures in the ring, bevelled surfaces at the outer ends of the rollers engaging with the frusto-conical surfaces of the recesses, and actuating means operable from outside the chuck body for shifting the sliding annulus longitudinally, and thereby forcing the rollers radially inwards.

2. A roller chuck for gripping bars, comprising: a chuck body formed with a frusto-conical recess at its inner end, an annulus longitudinally slidable and guided in the chuck body, the annulus being formed with a frusto-conical recess facing and co-axial with that of the chuck body, a ring located between and co-axial with the said frusto-conical recesses, the ring being formed with radial guiding apertures and also with two externally frusto-conical surfaces facing the frusto-conical recesses, neck portions projecting axially from the said ring, one of the said neck portions being guided in the sliding annulus, and the chuck body being formed with a

5 longitudinal aperture for guiding the other neck portion, rollers radially slidable in the apertures in the ring, bevelled surfaces at the outer ends of the rollers engaging with the frusto-conical surfaces of the recesses, an internal screw thread in the annulus, an externally screw-threaded member meshing with the said thread, bevel gear teeth on the externally threaded member, a bevel pinion journaled in the chuck body and meshing with the said gear teeth, and actuating means operable from outside the chuck body for rotating the said pinion, thus shifting the sliding annulus longitudinally and thereby forcing the rollers radially inwards.

3. A roller chuck for gripping bars as claimed in claim 2, further comprising a ball-thrust bearing interposed between the externally screw-threaded member and the chuck body.

4. A roller chuck for gripping bars as claimed in claim 1, further comprising tenons projecting from the double-coned ring that carries the rollers, the chuck body being formed with longitudinal guiding grooves in which the said tenons engage, so as to prevent the said ring from turning.
